UNITED STATES PATENT OFFICE.

EMIL ARTHUR SCHURIG, OF GROSSRÖHRSDORF, GERMANY.

HEDDLE.

1,109,306.

Specification of Letters Patent.

Patented Sept. 1, 1914.

Application filed November 15, 1913. Serial No. 801,274.

To all whom it may concern:

Be it known that I, EMIL ARTHUR SCHURIG, a subject of the Emperor of Germany, residing at Grossröhrlsdorf, Saxony, Germany, have invented certain Improvements in Heddles, of which the following is a specification.

The present invention relates to heddles particularly for use in weaving endless bands, its object being to produce heddles which can be easily applied to and removed from the endless warp.

The invention consists in the provision of two superposed strips having open-ended slots extending through little more than half the strip length. These strips are placed so that the slots run in opposite directions and form, at the inner end of the slots, an eye for the reception of the warp thread. The portions of the strips which form the eye are depressed in opposite directions so that the strips can be held in the same plane as the thread.

In the accompanying drawings the invention is illustrated, Figure 1 representing a side view of one of the strips, Fig. 2, a front view of the two strips arranged in juxtaposition, Fig. 3, a front view of the joined strips as applied to the warp thread, and Fig. 4, a side view of Fig. 3.

The heddle is composed of two superposed strips 1 each of which has an open-ended longitudinal slot 2 carried through a little more than half its length. The strips are

placed together so that the slots run in opposite directions and form in the middle of the strips an eye 5. The portions 3 and 4 of the strips which form said eye, are depressed in opposite directions, so that the strips can be held, as shown in Figs. 3 and 4, in the same plane as a warp thread 6 passing through the eye. The two strips are applied singly to the warp threads from opposite directions and then joined.

The heddles thus formed are fitted in the usual manner in a common heddle frame between spacing elements which hold the two strips of the different heddles together.

The subsequent removal of the heddles from the warp is easily effected by disassembling the strips.

I claim:—

A heddle composed of two superposed strips, each strip having a longitudinal open-ended slot carried through a little more than half the strip length, the strips being placed together so that the slots run in opposite directions and form an eye in the middle of the strip for the reception of the warp thread, the portions forming such eye being depressed in opposite directions so that the strips can be held in the same plane as the warp thread, substantially as set forth.

EMIL ARTHUR SCHURIG.
